UNITED STATES PATENT OFFICE.

ALBERT WILSON, OF STEUBENVILLE, OHIO.

WRENCH.

SPECIFICATION forming part of Letters Patent No. 771,195, dated September 27, 1904.

Application filed December 5, 1903. Serial No. 183,960. (No model.)

To all whom it may concern:

Be it known that I, ALBERT WILSON, a citizen of the United States, residing at Steubenville, in the county of Jefferson and State of Ohio, have invented new and useful Improvements in Wrenches, of which the following is a specification.

This invention relates to wrenches, and especially that class known as "sliding-jaw ratchet-wrenches;" and the purpose of the present improvement is to provide means whereby the sliding jaw of the wrench may be quickly adjusted with one hand within inclosures or at points where it is impracticable to use two hands to arrive at the result sought and also to include elements in the wrench structure of such positively-operating nature and strength that the sliding jaw will be held against accidental movement after adjustment thereof has been made.

The invention consists in the construction and arrangement of the several parts, which will be more fully hereinafter set forth.

In the drawings, Figure 1 is a side elevation of a wrench embodying the features of the invention. Fig. 2 is a similar view showing the sliding jaw in longitudinal section. Fig. 3 is a top plan view of the wrench. Fig. 4 is a detail perspective view of the sliding jaw. Figs. 5, 6, 7, and 8 are detail perspective views of parts carried by the sliding jaw.

Similar numerals of reference are employed to indicate corresponding parts in the several views.

The numeral 1 designates a shank having a handle 2 secured to one end and a stationary jaw 3 at the opposite end, one edge of the shank being formed with a series of ratchet-teeth 4, extending almost completely from the jaw 3 to the handle 2 and inclined in the direction of the jaw.

Adjustably mounted on the shank 1 is a sliding jaw 5, having an engaging face 6 to coöperate with the similar face of the jaw 3 when grasping a nut or other device. The jaw 5, as clearly shown by Fig. 4, has slotted guides 7, spaced apart from each other and of such dimensions as to permit the shank 1 to freely extend therethrough, and between the said guides in rear of the engaging face 6 the

said sliding jaw is formed with an integral cross-partition 8, with openings 9 at opposite terminals thereof for the reception of locking-blocks or sliding dogs 10, each having an inner transversely-serrated end 11 and an outer socket 12, as clearly shown by Fig. 8. Each block or dog 10 is freely slidable in its opening 9, and the serrations thereof form teeth to engage the teeth 4 of the shank 1, the serrations or teeth 11 of the blocks or dogs 10 having such direction as to freely slide over the teeth 4 when the jaw 5 is moved toward the jaw 3. The sockets 12 of the blocks or dogs 10 are disposed inwardly toward each other and located outwardly a suitable distance from the outer surface of the partition 8. The ends of a rocking lever 13 are movably held in the sockets 12 of the blocks or dogs 10, said lever having its outer edge formed with a central angular apex or projection 14, which is held in continual engagement with the inner side of a longitudinally-disposed spring 15 in the form of a resilient strap having an angular securing-terminal 16, which is fastened to the front portion of the jaw 5, and a rear slotted extremity 17, secured on a boss 18, projecting outwardly from the rear extremity of said jaw 5.

To the center of the rocking lever 13 the front bifurcated extremity 19 of a finger-piece 20 is pivotally secured, the arms of the bifurcation having their front extremities drawn in close relation to embrace the lever, and in rear of said extremities are spread apart a sufficient distance to embrace the boss 18, to which the finger-piece is fulcrumed. The finger-piece has a rear finger-engaging extremity 21 with a slightly-roughened upper surface, and said finger-engaging piece projects far enough rearwardly to be easily reached by one finger of the hand grasping the handle 2.

When it is desired to open the jaw 5 or move said jaw rearwardly toward the handle 2, the finger-piece 20 has pressure applied thereto in such direction as to move the finger-engaging extremity thereof inwardly toward the shank 1 and throw the bifurcated extremity outwardly. Said movement of the bifurcated extremity 19 will correspondingly

move the lever 13 against the resistance of the spring 15, and the locking-blocks or dogs will be disengaged from the teeth 4. The sliding jaw can then be adjusted toward the 5 jaw 3, as may be desired, by pushing forwardly thereon, and during this operation the locking-blocks or dogs 10 alternately engage portions of the teeth 4, so that one block or dog is always in locked engagement with 10 the said teeth. Rearward movement of the jaw 5 from the jaw 3 will be obstructed by the one locking-block or dog engaging the teeth 4, and by means of the sensitive rocking operation of the blocks or dogs 10 the 15 jaw 5 can be pushed toward the jaw 3 when the wrench is used with one hand without liability of said jaw 5 slipping backwardly.

The advantages of the improved construction are manifold, and particularly from a 20 standpoint of convenience and durability. All the parts can be readily assembled and are economical in the cost of manufacture.

Changes in the proportions, dimensions, and minor details may be resorted to without 25 departing from the spirit of the invention.

Having thus fully described the invention, what is claimed as new is—

1. A wrench, having a shank with a fixed 30 head and ratchet-teeth along one edge, a sliding jaw on the shank, toothed locking-blocks slidably mounted in the latter jaw and spaced apart from each other, a rocking lever connecting said blocks, a spring engaging said

lever, and means movably attached to the lever for throwing both blocks out of engagement from the teeth of the shank. 35

2. A wrench, having a shank with ratchet-teeth along one edge and a fixed jaw, a sliding jaw engaging the shank, a pair of locking-blocks to engage the teeth of the shank, said 40 blocks being spaced apart from each other, a rocking device connecting the outer extremities of said blocks, and operative means movably attached to said lever and to the sliding jaw for throwing both blocks out of engagement from the teeth of the shank. 45

3. A wrench, having a shank with ratchet-teeth along one edge thereof and a fixed jaw, a sliding jaw engaging the shank, locking-blocks movably mounted in the sliding jaw 50 and spaced apart from each other, a rocking lever connecting the outer extremities of the said blocks, and having an intermediate projecting portion at the outer edge thereof, a spring engaging said projecting portion of the 55 rocking lever, and an operating means movably attached to the lever and a part of the jaw for throwing the blocks out of engagement from the teeth of the shank.

In testimony whereof I affix my signature in 60 presence of two witnesses.

BERT. WILSON.

Witnesses:

ROBERT LOVE,
JOHN A. MANSFIELD.
